UNITED STATES PATENT OFFICE.

JAMES C. GARNER, OF HOUSTON, TEXAS.

COTTON SEPARATOR AND RENOVATOR.

Application filed February 3, 1920, Serial No. 355,931. Renewed July 18, 1923.

To all whom it may concern:

Be it known that I, JAMES C. GARNER, a citizen of the United States, residing at Houston, in the county of Harris and State 5 of Texas, have invented certain new and useful Improvements in Cotton Separators and Renovators, of which the following is a specification, reference being had therein to the accompanying drawing.

This invention relates to improvements in mechanism for treating cotton and preparing it for the market; particularly cotton which for one reason or another is classed as of a low grade. Large masses of such inferior grade are brought to central points after they have been treated in gins, at more or less distant places, in the farming territory. Other masses come from warehouses, sampling places, or compress mills. Some 10 comes in loose form; some in bales. In every case some will be of one color; some of another. Any given bale may contain masses of lighter colored grade, and others of darker color. A large proportion of any such mass 15 is composed of fibers, each of which has at one time or another been, as an individual, separated from the others adjacent to it: these including fibers which are of good color and luster and also fibers whose 20 color has been deteriorated by mildew or other cause. But intermingled with the separated or individualized fibers (some of superior, some of inferior color) in such 25 masses are large numbers of "motes" (undeveloped seeds with more or less lint attached) and clots or lumps of fibers which 30 have never been disintegrated or separated one from the other. And in addition to the 35 three specified components of such a mass, 40 there will be also intermingled large numbers of earthy particles, sand, grit, and the like, and numerous minute pieces of stalks, stems, leaves or trash.

The object of the present invention is to 45 provide a mechanism which will remove the individualized or already separated fibers, in a mass such as aforesaid, first from the hard particles or objects mentioned (as particles of earth, sand, grit, stalks, leaves and 50 the like), and from, secondly, the "motes" and the clots or small lumps of non-disintegrated fibers; and return the latter to the point of initial treatment again and again 55 until all of the fibers in the initial mass have been separated one from the others, and then taken out as the desirable product.

Another object is to do this in such way that the cleaned and separated fibers will constitute a mass or grade which is high in cleanliness, color and luster.

Fig. 1 is a front elevation of a machine embodying the present improvements.

Fig. 2 is a rear elevation of the same.

Fig. 3 is an end elevation as seen from the right when considering Fig. 1.

Fig. 4 is an end elevation when looking at the opposite end.

Fig. 16 is a section on the line 16—16 of Fig. 17.

Fig. 17 is a section on the line 17—17 of Fig. 16.

Fig. 18 shows the worm and worm wheel in the train transmitting power to the feed rolls.

Fig. 19 is a section of the reversing devices taken on the line 19—19 of Fig. 20.

Fig. 20 shows the casing for the reversing gear and the lever attachment.

Fig. 21 shows the clutch connection for the reversing lever.

The operative parts of the mechanism are supported on a framework and within a housing. The frame comprises uprights 2, 2 of a suitable number together with longitudinal bars 3, 4, properly disposed to give effectual support. To the frame are fastened end walls 5, 6.

In the upper part of the structure a hopper is provided at 7, which can be extended upward if desired as indicated at 8, and into

this the material is initially delivered. The front wall 25 of this hopper is supported by a hinge at 26 mounted in the side walls. And it can be adjusted in position and secured by fastening devices at 28.

In the lower part or mouth of the hopper are feed rolls 43 and 44. The devices by which these are mounted and actuated will be described below.

10 Immediately below the feed rolls is positioned the gin saw cylinder, indicated as an entirely by 37. Its component elements are carried by the shaft 38 mounted in suitable bearings supported on the framework. To 15 this shaft is fitted and keyed an elongated hub 38^a having a surface which is polygonal, preferably octagonal, in section. On this hub are fitted ring-like segments 40. Each is composed of a plurality, here eight, integral sections 40^a, each section being offset, axially, in relation to the sections next adjacent to it. And the radial faces (right and left) of each section lie in radial planes other than the planes of the faces of the 25 adjacent sections. The large central aperture of each of these ring-like segments 40 is polygonal in correspondence with the solid central hub 38^a.

39, 39 indicate the sectional saw blades. 30 Each is formed with a main tapering plate part 39^a, 39^b. The part 39^a fits in one of the radial recesses 40^b in one of the ring sections 40. The part 39^b extends outwardly beyond the periphery of the ring or washer 35 section. Each solid section has a peripheral projection at 39^a and at the opposite edge is cut away somewhat as at 39^b. At the inner edge each has a lip flange 41 extending at right angles to the plane of the saw. 40 These lip flanges 41 are of such thickness that a circular series of eight of the saw sections can be positioned around the axis and have the flanges 41 rest upon the flat faces of the hub 38^a, each of the washer 45 rings or clamps 40 being adapted to be fitted into position and surround the series of flanges 41 pressing them tightly against the hub 38^a, and thus firmly and securely holding all of the circular series of saw sections 50 in position and prevent them from flying or moving outward or radially away from the axis.

Because of this radially stepped or offset relationship, in positions, of the saw sections 55 in each circular series provision is made for having a complete cylinder generated by the saw teeth. That is to say, any straight line parallel to the axis and at a distance equal to the radius of the saw teeth will have each 60 of its points intersected by a long series of teeth at each rotation of the cylinder.

All of the component parts are firmly bound together by nuts 42 engaging with threads on the shaft 38.

65 The material from the hopper 7 is by the

feed rolls 43, 44, formed into a compact web. As it moves down from the contact lines of the feed rolls this web is immediately presented, along a line parallel to the axis of the gin cylinder. A large number of 70 teeth pass through each point of this line at each revolution of the cylinder and the latter is rotated at high speed.

The web of material may be regarded as composed of (first) individual lint fibers 75 more or less separated from its neighbors, (2nd) small clots or lumps each comprising a large number of fibers which have never been separated one from the other, but which are susceptible of such separation, (3rd) 80 "motes" small objects disseminated through cotton masses and supposed to be imperfectly developed seeds or growths, (4th) small pieces of stalks, stems and leaves which have become intermingled with the cotton fibers, and (5th) particles of earthy matter, 85 grains of sand, and the like.

When the rapidly rotating saw teeth impinge upon the extreme edge part of the down forced web the already separated or 90 loosened lint fibers are one by one rapidly caught by the teeth and cannot escape therefrom. They slip into the recesses 39^a between the teeth 39^b, matting tangentially inward, as indicated at 39^c, Fig. 10. Those caught at points adjacent the feed rolls are 95 instantly thereafter, at nearly the termination of a rotation, removed by the doffing devices.

Bodies of the other four classes above 100 specified (small fiber clots, small "motes", minute stem pieces and grains of earth or sand) are thus instantly separated from the valuable lint fibers which are carried away by the teeth. The latter, with their high 105 velocity, strike these small objects and drive them forcibly outward tangentially. Those that are driven with the most force impinge on a curved imperforate breast plate 32, 110 these generally being the heavier sand grains, earthy particles and the like. The "motes" are not driven so violently and impinge upon an inner concave perforated breast plate 29. They pass through the perforations and are 115 collected in a trough 34 together with the particles of foreign materials which are deflected downward by the outer breast plate 32.

The small clots or lumps of more or less 120 tightly wound fibers tend to be also caught by the points of the cylinder teeth and to be carried around by them together with the desired fibers. In order to stop their passing completely around, a picker roll 51 is 125 positioned below the saw cylinder, where its teeth can catch the lumps or clots adhering to and projecting beyond the surface of the cylinder. This picker roll rotates, as will be described, in a direction opposite to that of the rotation of the saw cylinder 130

so that the adjacent teeth of the two elements travel in the same direction and those on the picker roll can easily take the lumps of fiber away from those on the gin cylinder.

5 After the picker has detached them they drop into the hopper like receptacle 52 whence they are taken in a manner to be described.

The desirable lint fibers which move beyond the picker roll 51, after they have been separated as above described from all undesirable particles and objects, are rapidly removed from the saw cylinder by the doffing cylinder or drum 49. This rotates with a peripheral speed much higher than that of the gin saw cylinder, and its periphery is composed of tufts which sweep the saw teeth in such direction as to clean the fiber out from all of the recesses in front of the teeth of the saw disk. The fiber that is thus removed by the doffer drum is forced upward along the duct 49^a to the large take away duct 49^b, through which it is propelled by air to a suitable bin or collecting place.

25 The "motes," sand, grit, earthy particles, pieces of stems and leaves, which have been forced outward against the breast plates 32 and 29, and finally collected in the trough 34, are taken by the conveyer 35 laterally across the machine and delivered through the discharge chute 36.

The lumps of knotted or still unopened cotton fibers which are removed from the gin drum by the picker roll 51, and, as above stated, drop into the hopper or chute way at 52, pass out of the latter into the duct 53. From this they are drawn by the fan 54 to its casing 55 and are forced thence up the duct 55^a to a receiving chamber 56 which tapers from the point at 56^a, where it is connected to the duct 55^a, laterally toward the ends of the machine. This chamber has a laterally tapering bottom 47, a similarly tapering top wall 46, and a vertical front wall 46^a. It is divided by a perforated diaphragm 47^a parallel to the bottom wall 47. Exhaust pipes 57 communicate with the interior of the upper part of this chamber. The materials which are forced upward through the duct 55^a and are delivered at 56^a to the receiving chamber, pass down upon the floor or bottom 47 toward a discharge mouth 45 through which they pass again into the initial feed hopper 7. As they are moving along the floor 47 they are subjected to suction draft and any dust or like particles which they carry or which have been shaken loose from them will be drawn up through the perforated diaphragm 47^a and carried out through the ducts 57. 45^a are rollers at the discharge mouth 45 which can be used to force the material into the hopper 7, and which also serve as cut offs to prevent air being drawn inward through the mouth.

By the devices last described large quantities of valuable cotton are recovered and saved; it being that part of the mass made up of what have been referred to as clots or lumps of unopened cotton fiber, and which pass the gin cylinder 37 without having their fibers individually separated each from its neighbors. After being returned, as above set forth, to the hopper 7 they are again passed through the train of disintegrating devices, and finally their fibers become completely disintegrated.

The inner concave breast plate 29 is mounted on hinges at 29^a and can be adjusted, at its upper edge, toward and from the gin saw cylinder by the screw devices at 29^b. The cotton masses initially supplied vary in their composition and in the conditions of the components, and under some circumstances it is necessary to throw the upper edge of the breast plate 29 outward in order to permit all of the small clots or lumps of cotton fibre to pass down on the inside of the breast. The inner edge of this breast plate is positioned close to the picker roll so that if any of the clots or lumps of cotton should move downward without being in engagement with the cylinder teeth they will reach positions where they must be caught by the teeth of the picker roll and carried around and dropped into the ducts which return them to the initial hopper 7.

The devices by which power is transmitted to the mechanism, as an entirety, and is distributed to the several moving parts are as follows:

The shaft 38 of the gin cylinder is provided with a pulley 59 with which a main driving belt 58 engages. On the opposite end of the shaft 38 there is a pulley 61. 62 is a belt engaging therewith and also with a pulley 66 on the shaft 49^c of the doffer drum, the belt passing around, and returning from, an idler pulley 63. The latter is mounted in a yoke 64 which, in turn, is mounted at 65 on the frame. 65^a is an arm rigid with the yoke 64 and carrying a pivoted nut 65^b at its lower end. With this nut an adjusting rod 65^c engages by means of a thread at 65^d. The rod 65^c extends to the front of the machine where it is provided with a hand wheel 65^e by which it can be turned when it is desired to swing the arm 65^a and the yoke 64 to tighten or loosen the belt 62.

In order to have the circles of rotation of the ends of the gin cylinder teeth and the circles of rotation of the extremities of the doffer tufts delicately adjustable in relation to each other the bearings of the shaft 38 of the cylinder and of the doffer shaft 49^c are carried by slide plates which are adjusted by screws as shown in Figs. 3 and 4.

On the opposite end of the doffer shaft 49^c there is a pulley 49^d and this drives a

belt 49^a which engages with the pulley 54^a on the shaft of fan 54. 39^a is a small pulley on the end of the cylinder shaft 38 and this by means of belt 57 drives a pulley 68 on the end of shaft 68^a. This shaft extends into a gear box 69 and carries a bevel wheel 70. The latter engages with two loose opposite bevels 71 and 72 on shaft 75. A clutch 73 can engage at option 10 with either bevel 71 or 72. The bevel 72 is connected to a smaller bevel 76 which in turn engages with and drives the bevel 77. The shaft 77^a of this wheel extends outward and carries a sprocket wheel 78 which 15 through chain 79 rotates the sprocket wheel 80 on the shaft 51^a of the picker roll 51. A second chain 81 is driven from the roll shaft and, in turn, drives the shaft 35^a of the conveyor 35. 20 The clutch 73 is shifted by the lever 74 mounted on the gear box and accessible at the front of the machine. The feeding rolls 43 and 44 are driven with optionally variable speeds. The shaft 25 75 extends to the rear of the machine and carries a three-speed belt pulley 90. 91 is a belt extending upward to a three-speed pulley 92. This is on the end of a shaft 92^a which is mounted in a swinging bearing 95, 30 the bearing being adjustable by turn buckle devices having the rods 96 and 98 pivoted, one to the machine frame, and the other to the bearing, together with the threaded adjuster 97. The bearing element 95 for the 35 shaft 92^a swings around the axis of a shaft 94 mounted in bearings 94^a on the frame. The shaft 94 is driven by gears 92^b and 92^c, and extends towards the front of the machine and into the gear box 94^b. It carries 40 a worm 101 which engages with a worm wheel 102 on a short shaft 103. This shaft also carries a spur gear 88 which meshes with a wheel 84, that is keyed to the shaft of the feed roll 43, and meshes also with 45 an idler gear 86^a. 85 is a swinging bearing carrier pivoted on the axis of the idler gear 86^a, and at its lower end supporting the other feed roll 44, the latter having a pinion 88 meshing with the idler gear 86^a. The 50 swinging bearing carrier 85 is normally held in a predetermined position by a rod 86 and spring 87; but the spring permits the bearing and the feed roll 44 to yield away from the roll 43 when demanded by the material 55 which is passing between the rolls; the swinging roll, however, being constantly positively driven by the power.

The manner in which the machine is used will be readily understood. The masses of 60 cotton with the intermingled foreign materials, above described, are delivered to the hopper 7 either in the form of a continuous bat or more or less miscellaneous. The rolls feed the mass downward as a continuous bat. The teeth of the rapidly rotating

gin cylinder impinge on the articles at the front extremity of the bat. They catch each 70 separate individual fiber and positively engage with it and carry all of the fibers around on the edge of the saw.

The small solid particles (which are intermingled with the cotton in the advancing bat) are freed when the lint fibers are caught by the teeth and pulled from the bat and carried swiftly away from these particles; the latter being particles of earth and sand or similar materials. And simultaneously, the small pieces of stalks, leaves, and similar trash, are freed as the individual fibers are carried away by the teeth. 75 But such particles are simultaneously struck by the cylinder teeth and are projected forward by their blows; and the devices of the mechanism are adjusted to permit particles of the sort just referred to to pass over the upper edges of the inner breast plate and be caught by or impinge on the outer breast plate, and the latter deflects them or turns them downward toward the trough 80 34. 90

The bodies of the other two classes above specified ("motes," and the small clots or lumps of non-disintegrated fiber) are also freed more or less from the instant that the rapidly moving teeth catch and carry away the separated fibers; but these "motes" 95 and clots are not driven so far forward by the cylinder teeth. They are carried downward more directly and pass into the space between the saw cylinder and the inner breast plate 29. The "motes," as they pass 100 down, tend to sieve through the perforations in the breast plate 29 and accumulate with the earthy and other particles in the trough 34.

The clots or small lumps of intertwined fibers tend to remain outside the circles of rotation of the points of the teeth, though many of them are caught by the extreme tooth points, while others work downward through the channel inside of the breast plate and more or less free from the saw. In either case the teeth of the picker roll 15 catch them; those that are adhering to the saw tooth points being removed by the picker although held for an instant to permit disintegration of the fibers; and after removal they are dropped into the passage-way through which they are carried back to the initial hopper to again pass through the machine for further disintegration. 110 Those clots which tend to move down outside the circles of the tooth points finally reach the picker rolls at the lower edge of the breast plate and the roll teeth carry them 115 up and through the narrow space below the saw cylinder where disintegration, more or less, occurs and the residues of the clots are returned, as aforesaid.

The continuing of the operation of the machine finally results in the producing of 120 130

two masses, the one being the mass of separated or individualized fibers, and the other being the mass of grit, sand, earthy particles and small pieces of trash, together with the 5 "motes." The first of these masses has the fibers so thoroughly and homogeneously intermingled that the resulting body is one of a grade uniformly high in cleanliness, color and luster.

10 What I claim is:

1. In a machine for separating and cleaning cotton fibers and improving the grade of masses of such fibers, the combination of the bat-forming and gripping feed rolls, a 15 toothed cylinder immediately below said rolls, having fiber-catching teeth arranged to engage with the fibers at the forward edge of the web gripped by the rolls and to project grains and particles of foreign matter 20 laterally outward, means for collecting and separately delivering said foreign particles, means for removing the separated lint fibers caught by the cylinder teeth, means for taking away from the cylinder the small clots 25 of unseparated fibers and preventing them from again commingling with the said foreign grains or particles, and means for returning the said clots to the feed rolls.

2. In a machine for separating and cleaning cotton fibers and improving the grade of 30 masses of such fibers, the combination of a cylinder having fiber catching teeth so positioned and of such number as to generate when rotating a complete cylinder, means 35 for feeding a bat and holding it rigid at points near the cylinder, means for removing the separated fibers which are caught in the teeth, means engaging with the small masses of unseparated fiber and advancing 40 such masses first toward and then away from such teeth, means for forming a chamber immediately adjacent the cylinder teeth to receive motes and small masses of unseparated 45 fiber, means for forming a second chamber outside of that aforesaid for receiving foreign particles separated from the cotton, a wall for separating the said chambers and means for returning to the region of initial supply the said small masses of unseparated 50 cotton.

3. In a machine for separating and cleaning cotton and improving its grade, the combination with feed rolls arranged to form a compact bat, a cylinder having teeth arranged to intersect all points of each transverse line of the approaching bat, a picker roll below and immediately adjacent the cylinder, a perforated concave breast wall having its lower wall close to the circle of 55 rotation of the picker roll, an outer imperforate breast wall, a hopper to which the picker roll delivers the non-disintegrated cotton, a trough and conveyer adjacent to 60 said hopper arranged to receive the material from the outer breast wall and also that

which passes through the perforated inner wall, and means for pneumatically returning to the feed rolls the said non-disintegrated cotton, all of said means being arranged to first separate particles of grit and 70 foreign material from the cotton and thereafter separate the non-disintegrated cotton from the cylinder and prevent its commingling with said foreign particles.

4. In a machine for separating and cleaning cotton fibers and improving the grade of masses of such fibers, the combination of an initial feed receptacle, feed rolls, a toothed cylinder, means for taking the small masses of unseparated cotton fibers 80 from the cylinder and conveying them toward the initial feed receptacle, said means including a duct and a receiving chamber into which they are delivered from the duct, and means for pneumatically screening said 85 masses as they pass through said chamber.

5. In a machine for separating and cleaning cotton fibers and improving the grade of masses of such fibers, the combination with feed rolls arranged to form a compact bat, a cylinder having teeth arranged to intersect all points of each transverse line of the approaching bat, said teeth being in sets, all of the teeth of each set lying in a plane 90 transverse to the cylinder axis and said plane being other than the transverse planes in which lie the teeth of the adjacent sets, a toothed picker roll below and immediately adjacent to the cylinder, an inner breast plate extending to a line near the periphery 95 of the picker roll, an outer breast plate, a duct for carrying disintegrated cotton away from the picker roll, a duct for carrying the lint fibers away from the cylinder, and a duct arranged to receive particles of material 100 guided downward by the breast plate.

6. In a machine for separating and cleaning cotton fibers and improving the grade of masses of such fibers, the combination of an initial receptacle, a toothed saw cylinder, 110 means for finally removing from said cylinder the separated fibers caught thereon, means for removing from the cylinder small clot masses, means for returning the said masses to the initial receptacle, a chamber 115 through which said masses pass as they are returning, a perforated diaphragm in said chamber adjacent to the path of the said masses, and suction means for causing fine particles to pass through the said diaphragm.

7. In a machine for separating and cleaning cotton fibers and improving the grade of masses of such fibers, the combination of feed rolls, the saw cylinder arranged to 125 project foreign particles laterally, a duct for receiving said foreign particles and preventing them from again commingling with the cotton, a picker roll, a doffer drum, a conveyer for receiving and taking away the par- 130

6
ticles of material driven out of the cotton mass by the impact of the saw teeth, a prime power device connected to the saw cylinder, and power transmitting devices connected with and actuated by the saw cylinder and connected to said picker roll, to said doffer drum and to said saw cylinder.

8. In a machine for separating and cleaning cotton fibers and improving the grade of masses of such fibers, the combination of bat-forming and gripping feed means, a toothed cylinder immediately adjacent said means, having fiber-catching teeth arranged to engage with the fibers at the forward edge of the web gripped by the said feed means and adapted to project grains and particles of foreign matter outward, means for collecting and separately delivering said foreign particles, means positioned around the circumference of said cylinder for taking away from the cylinder the small clots of unseparated fibers and preventing them from again commingling with said foreign grains or particles, means for removing the sepa-

rated lint fibers caught by the cylinder teeth, and means for returning the said slots to the feed means.

9. In a machine for separating and cleaning cotton fibers and improving the grade of masses of such fibers, the combination of feed rolls adapted to form and advance a bat, a cylinder adjacent said rolls having fiber-catching teeth which are arranged to generate in rotation a complete cylinder, means for collecting and separately delivering foreign particles which are thrown outward by said cylinder, means for taking away from the cylinder small clots of unseparated fibers and preventing them from again commingling with said foreign particles after the latter are once thrown outward by the cylinder, means for pneumatically returning said clots to the feed rollers, and means for removing the separated lint fibers caught on the teeth of said cylinder. 40 45

In testimony whereof I affix my signature.

JAMES C. GARNER.
